UNITED STATES PATENT OFFICE.

HERMAN A. DE VRY, OF CHICAGO, ILLINOIS, ASSIGNOR TO THE DE VRY CORPORATION, OF CHICAGO, ILLINOIS, A CORPORATION OF ILLINOIS.

MOTION-PICTURE MACHINE.

1,287,576.

Specification of Letters Patent.

Patented Dec. 10, 1918.

Application filed March 23, 1916. Serial No. 86,073.

To all whom it may concern:

Be it known that I, HERMAN A. DE VRY, a citizen of the United States, and a resident of Chicago, in the county of Cook and State 5 of Illinois, have invented certain new and useful Improvements in Motion-Picture Machines, of which the following is a full, clear, and exact description.

The invention relates to kinetoscopes. In 10 projecting apparatus for motion pictures, a desideratum has been to provide a portable machine in which the entire apparatus, including the illuminating means, is contained in a single case. In an application filed by 15 me August 16, 1915, Serial No. 45,632, there is disclosed such apparatus.

In practice, it has been found that when, in places where an incandescent lamp of 20 very high candle power is necessary, the residual heat in the case raises the temperature in the case to an objectionable degree. The object of the present invention is to provide an improved machine, in which provision is made for forcibly and efficiently carrying off 25 the heat to render the apparatus safe in operation, particularly when an incandescent lamp of high candle power is employed for projecting the pictures on the film.

A further object of the invention is to provide 30 means for forcibly carrying away heat from the case without additional operating mechanism, and in the attainment of this object, the rotating shutter is utilized to force the air through the objective opening 35 in the case.

The invention further designs to provide an improved portable projecting apparatus for motion pictures.

The invention consists in the several novel 40 features hereinafter set forth and more particularly defined by claims at the conclusion hereof.

In the drawings: Figure 1 is a side elevation of a machine embodying the invention, the hinged cover being open and one side of the lamp box being removed. Fig. 2 is a horizontal section taken on line 2—2 of Fig. 1. Fig. 3 is a transverse section through the case and lamp box on line 3—3 of Fig. 1. Fig. 4 is a central vertical section on line 4—4 of Fig. 2.

The apparatus is inclosed within a rectangular case comprising a bottom 9, a front 10, a back 11, a top 12, a fixed side-wall 14 55 and a cover 15 hinged to the back, as at 16,

so that it may be swung open for convenient access to all of the mechanisms and devices in the case. The cover 15 forms one side of the case. Film spools 18 and 19 are mounted side by side in the lower portion of the case. 60 Spool 18 serving as a supply spool and spool 19 as a take-up for the exposed film.

A film-feeding mechanism is mounted in a frame 17 which is secured to the fixed side 14 of the case. An electric motor A, secured 65 on the back-wall 11 of the case by posts 11^a furnishes the power for driving the film-feed mechanism. The film-feed mechanism comprises a continuous feed-sprocket 59 and a continuous take-up sprocket 61 both 70 mounted on a shaft 88; an intermittent feed-sprocket 60; a shutter-shaft 76; a pinion 92 secured to the shutter-shaft and meshing with a pinion 93 on a shaft 94 which is driven by a belt *a* and a belt-pulley 98 from 75 the motor A; a gear-train comprising a gear 91 on the shutter shaft and a gear 90 on the continuous feed shaft 88 for driving the continuous feed sprockets; a shaft 80 provided with a belt pulley 85 for driving a belt 86 80 which operates the take-up spool 19; and a Geneva gear connection between shaft 94 and shaft 99 for intermittently operating the sprocket 60. From the supply spool 18, a loop of the film 21 passes around feed- 85 sprocket 59 thence around idler rolls 63, thence across the picture openings 67 in a plate 65, thence around idler roll 68, thence around the intermittent feed-sprocket 60, thence to the continuous take-up sprocket 61 90 and thence to the take-up spool 19. It will be understood that suitable rollers will be provided for guiding the film and for keeping it in engagement with the feed sprockets, but since the construction of these form no 95 part of the present invention, it is not deemed necessary to illustrate and describe them in detail. For a detailed illustration and description of these devices, reference may be had to an application filed by me 10 Aug. 16, 1915, Serial No. 45,633. The mechanism thus far described exemplifies a film supply and take-up and film-feeding mechanism and a motor for operating said mechanism all inclosed within a case and operatively connected together therein.

Suitable projecting lenses 73 are mounted in a tube 74 in alignment with the picture opening 67 and an objective opening 77. A shutter 75 comprising a plurality of blades 110

75^a is fixed to the front end of shaft 76 and is continuously rotated by said shaft. A plurality of these blades is provided to cut off the light during the movement of the 5 film and also to prevent flickering. These blades are angled relatively to the plane of rotation so that they will act as a fan to force air through the objective opening 77, as well as cutting off the passage of light 10 through the film for a purpose presently set forth.

The lighting apparatus comprises an incandescent electric lamp 40 held in a lamp socket 41 on a bracket 42 which is fixed to 15 the back wall of the case. A tube 43 for the condensing lenses 44 is mounted in a partition 24 between the film and the lamp. An electric switch 60 is secured to the back 20 of the case and is electrically connected to the lamp socket 41 and the motor A in manner well understood in the art. The lamp 40 is disposed in a box 50 in a compartment 24^b formed in the case between partition 24 and the back wall of the case. 25 Motor A is disposed in the lower portion of said compartment. The inside of this box is usually painted white and comprises fixed bottom, front, back and top walls, all separated from the walls of the inclosing case 30 to form an air passage between the box walls and the case-walls. This box is supported by bracket 42, and posts 42^a. The side of the box adjacent the cover is removable to provide access to the lamp in the box when 35 desired. An air inlet 45, over which extends a screen or guard 47, is formed in the side-wall 14 of the case to admit air to the compartment 24^b below the lamp-box. An air opening 65 is formed in the top wall 40 of the case above the lamp box, and a screen or guard 65' is secured over this opening. Openings 54 are formed in the bottom of the lamp-box for air to pass from the compartment 24^b into the lamp box. An opening 55 is formed in the top of the lamp box. The purpose of these openings is to provide 45 a passage for air.

Motor A is provided with a fan a' disposed adjacent air-inlet 45. This fan will 50 be operated while the machine is in operation and forces air entering compartment 24^b at inlet 45, through openings 54 into the lamp-box. This air passes around the lamp and forces the heat through openings 55, 65, 55 to the outside of the case. Air is also forced around the outside of the lamp-box to the outlet 65. An opening 56 is formed in the case to admit air to the main compartment of the case containing feed mechanism, and 60 the fan-blades of shutter 75 force air through the objective opening 77. These forced currents of air serve to efficiently keep the case and its contents cool and render safe the operation of the film in close 65 proximity to the lamp contained in the case.

This apparatus exemplifies one in which air is forced through the case containing the lamp to carry off heat from the lamp and to prevent all of the parts from becoming unduly heated. The invention also 70 exemplifies a machine in which cooling is effected by the shutter. The invention is particularly advantageous in a portable machine in which it is desired to have the inclosing case as small as possible and in which 75 a lamp of exceptionally high candle power is necessary.

The operation of the shutter and film feeding mechanism will be as follows: Motor A will operate the belt a to drive pulley 98 80 and its shaft 94 continuously. Gear 93 on shaft 94, meshing with gear 92, will operate the shutter shaft 76 continuously. The intermittent driving connection between the pulley 98 and sprocket 60 will serve to operate said sprocket to feed the film intermittently across the exposure opening 67. Gear 91 on the continuously rotating shaft 76 meshing with gear 90 will operate the continuous feed sprocket 59 and the take-up 85 sprocket 61 continuously. Gear 89 meshing with gear 87 on shaft 80 will rotate pulley 85 to operate the belt 86 for operating the take-up spool. During the operation of the machine, the fan a' and shutter 75 will 90 operate to force air-currents through the case to carry off heat from the lamp.

The invention is not to be understood as restricted to the details set forth, since these may be modified within the scope of the 100 appended claims, without departing from the spirit and scope of the invention.

Having thus described the invention, what I claim as new and desire to secure by Letters Patent, is:

105

1. In a moving picture machine, the combination of a film supply, film-feed mechanism, means for driving said mechanism, illuminating means, a box around said illuminating means, a portable carrying case 110 containing said supply, feed mechanism, driving means and box, and means for forcing a current of air through and around the outside of said box.

2. In a moving picture machine, the combination of a film supply, film-feed mechanism, means for driving said mechanism, illuminating means, a box around said illuminating means, a portable carrying case containing said supply, feed mechanism, 120 driving means and box, said case and box each having inlet and outlet openings therein, and means for forcing a current of air through said openings.

3. In a moving picture machine, the combination of a film supply, film-feed mechanism, means for driving said mechanism, illuminating means, a box around said illuminating means, a portable carrying case having an air opening in its top and con- 125 130

taining said supply, feed mechanism, driving means and box, and means for forcing a current of air through said box and discharging it through said opening.

5 4. In a moving picture machine, the combination of a film supply, film-feed mechanism, means for driving said mechanism, illuminating means, a box around said illuminating means having an air inlet and 10 an outlet, a portable carrying case having an opening in its top and containing said supply, feed mechanism, driving means and box, and means operated by said driving means for forcing a current of air 15 through and around the outside of said box and discharging it through said top opening.

5. In a moving picture machine, the combination of a film supply, film-feed mechanism, means for driving said mechanism, illuminating means, a rotating shutter operated by said mechanism, a portable carrying case containing said supply, feed 20

mechanism, driving means, illuminating means and shutter, a fan operated by said driving mechanism for forcing a current of 25 air around the lamp and through one portion of the case, said shutter having fan blades adapted to force air through another portion of the case.

6. In a moving picture machine, the combination of a film supply, film-feed mechanism, means for driving said mechanism, illuminating means, a rotating shutter operated by said mechanism, a case divided into separate compartments, one of which 30 contains said supply and feed mechanism, means and shutter, the other containing the illuminating means, a fan operated by said driving mechanism for forcing a current of air around the lamp and through one compartment, said shutter having fan blades 35 adapted to force air through the other compartment. 40

HERMAN A. DE VRY.
